(57) **CLAIM**

The ornamental design for a shaped pillow as shown.

DESCRIPTION

FIG. 1 is a top perspective view of a shaped pillow showing our new design;

FIG. 2 is a front elevation view of the shaped pillow of FIG. 1;

FIG. 3 is a rear elevation view of the shaped pillow of FIG. 1;

FIG. 4 is a right side plan view of the shaped pillow of FIG. 1;

FIG. 5 is a left side plan view of the shaped pillow of FIG. 1;

FIG. 6 is a top plan view of the shaped pillow of FIG. 1;

FIG. 7 is a bottom plan view of the shaped pillow of FIG. 1;

FIG. 8 is a front perspective view of the shaped pillow of FIG. 1; and,

FIG. 9 is a rear perspective view of the shaped pillow of FIG. 1.

The variable stippling shading and broken contour lines help to indicate the three-dimensional shape and contours of the design.

1 Claim, 8 Drawing Sheets
